SPRAY CAP

Joseph E. Benoit, Malverne, N. Y., and William F. Sanford, Riverside, Conn., assignors to Atlantic Plastics, Inc., Flushing, N. Y., a corporation of New York

Application October 14, 1949, Serial No. 121,298

1 Claim. (Cl. 299—89)

1 This invention relates to atomizing nozzles, and more particularly to a combination cap and atomizing nozzle which can easily and quickly be attached to or removed from the neck of a container.

With the advent of some of the newer plastics, it has become possible to manufacture inexpensively bottles and other containers that are flexible and have a certain amount of elasticity. For example, flexible and resilient bottles have been successfully made of polyethylene and have been used in conjunction with an atomizing nozzle of some type to dispense the bottle contents in the form of a fine mist or spray.

Considerable difficulty has been experienced, however, in obtaining satisfactory atomizing nozzles for such use that meet all the requirements. For example, a flexible bottle fitted with such a nozzle must be capable of being sealed tightly so that the contents of the bottle will not accidentally leak out or evaporate. Also, the nozzle must function effectively to produce a satisfactory spray every time the bottle is squeezed regardless of whether it is squeezed lightly or heavily. In addition, the nozzle must be one which allows air to return freely to the inside of the bottle when it is released so that the bottle after being squeezed will quickly regain its normal shape and be ready to produce another spray.

An object of our invention is to provide an atomizing nozzle which may be made in the form of a removable cap, which satisfies all of the foregoing requirements and at the same time is very economical to manufacture by mass production methods.

Another object of my invention is to provide such a cap and nozzle that can be made easily and in large quantities out of plastics by a simple rapid molding process.

We have also found that nozzles constructed like the preferred embodiments of our invention can be used to advantage for dispensing powders as well as for dispensing liquids.

Two embodiments of our invention are illustrated in the accompanying drawings, in which Fig. 1 is a side elevational view of a flexible bottle showing attached to the neck thereof a combination cap and atomizing nozzle with an overcap in place over the end of the nozzle.

Fig. 2 is a side elevational view of the bottle and cap on a larger scale, with the overcap removed and the main cap partly broken away.

Fig. 3 is a vertical sectional view through the nozzle, cap and neck of the bottle, taken approximately on the line 3—3 of Fig. 2.

2 Fig. 4 is a plan view of the combination nozzle and cap.

Fig. 5 is a bottom plan view of the nozzle and cap with some parts in section and taken on the line 5—5 of Fig. 3.

Fig. 6 is a perspective view on a larger scale of the overcap illustrated in position on the nozzle in Fig. 1.

Fig. 7 is a view similar to Fig. 2 but showing an alternative form of cap and spray nozzle.

Fig. 8 is a vertical sectional view through the center of this alternative form taken approximately on the line 8—8 in Fig. 7.

Fig. 9 is a plan view of this modified cap and nozzle.

Fig. 10 is a bottom plan view with parts in section and taken approximately on the line 10—10 of Fig. 8.

While certain features of our invention are not limited to use with caps for flexible bottles, the invention will be described by reference to such constructions as showing the best ways of utilizing the invention.

Referring particularly to Figs. 1 to 6, the nozzle and cap of our invention, shown generally at 10, may be shaped like an ordinary screw cap with an upward extending projection 17. This cap is provided with internal threads 11 to engage threads 15 on the bottle neck 12 so that it can be threaded on over the neck 12 of a flexible bottle 13. If desired, the bottle neck may be formed with a projecting annular ring 14 below the screw threads 15 of such dimensions that the skirt of the cap bears heavily against this ring when in place. The bottle itself may be made of any suitable flexible or resilient material, such as rubber or polyethylene, or, if desired, it may be made of more rigid materials but in the form of a bellows, or in some other form that can be compressed.

The upper side surface of the cap also may be formed with one or more circular grooves, as shown at 16, which have beveled edges or side walls to provide a tight fit with the upper edge 45 of the bottle if it is not made to close tolerances or is not exactly round in shape. Various other shapes or constructions may be used for securing and holding the cap tightly in place on the neck of the bottle.

The nozzle portion of the cap is formed in the external upward projection 17, which may be of generally cylindrical shape and formed integral with the top or main portion of the cap itself. Projection 17 is formed with a central passage 18 opening into the interior of the cap

and having a square or other suitable polygonal shape in cross section. This square opening terminates near the upper portion of the projection in a diagonal wall 19, which extends at an appropriate angle such as a 45° angle from one side of the square passage up to the opposite side thereof. Externally, the projection 11 is cut away, as shown at 20, along a plane approximately at right angles to the plane of the wall 19 and located just below the intersection of wall 19 and the longest wall of passage 18. This construction leaves an atomizing opening 21 for the nozzle which is preferably in the shape of a narrow slit.

A tube 22 is fitted into the nozzle passage 18 before the cap is placed on the bottle. Tube 22 may also be made of plastic or other suitable material and may be rigid or flexible, as desired. The tube illustrated is cylindrical in shape or circular in cross section and of such a diameter that it can be forced into the passageway 18 to provide a tight or press fit, as seen in Fig. 5. Tube 22 preferably is of sufficient length to extend to a point just above the base or bottom of the bottle 13.

It will be apparent that the cylindrical tube 22 in the square passageway 18 leaves spaces between the tube and passageway (Fig. 5) so that air can flow with a certain amount of freedom between these two elements.

In the operation of this device, the cap is first fitted with the tube 22 which has its end pressed into place in the passageway 18. The cap 10 is then screwed firmly onto the neck of the bottle 13, which has been filled to any desired level with the liquid or powder to be dispensed. When the walls of the bottle 13 are squeezed or compressed so that the air inside the bottle above the liquid is compressed, this produces a pressure inside the bottle which forces the liquid or powder to be dispensed up through the hole 23 in the tube 22 and at the same time this same pressure forces air to pass up the passageway 18 around the outside of the tube 22. The air and liquid or powder thus are mixed in the upper portion of the passageway 18, the mixture strikes the inclined wall 19 and is forced at considerable velocity out through the small opening 21 which, because of its shape and sharp edges, produces an atomizing action. A liquid thus dispensed can be easily formed into a fine mist or spray each time the bottle is squeezed. Finely divided powders, such as tooth powders, can also be dispensed either as a dusting operation or, if desired, with a slightly larger opening in the nozzle, to form a layer of the powder. For example, with the nozzle embodying our invention, it is possible to dispense tooth powder in such a manner as to spread a layer of it directly onto a toothbrush. This combined cap and spray nozzle may be easily made of plastic materials as an injection molding since there are no parts which have to be held to especially close tolerances.

The sealing of the device to prevent leakage or accidental escape of the bottle contents is made easy by the fact that the nozzle projects upward internally from the body of the cap. A simple overcap, as shown at 25 (Figs. 1 and 6), which fits tightly over the projection 11 may be used for this purpose. Of course, the overcap and projection may be threaded if desired to hold the overcap in place although that is not necessary.

Figs. 7 to 10, inclusive, illustrate a combination cap and spray nozzle according to our invention.

which has a slightly different construction from that illustrated in Figs. 2-5, inclusive. Where the parts are the same, the same reference numerals have been employed.

In this modified form, the cap proper, illustrated generally at 10, has internal threads 11 to engage the external threads 15 on the neck 12 of the bottle 13. If desired, the bottle may also be provided with a projecting ring 14 to spread and hold tightly in place the skirt of the cap 10. In this instance, the inside top face of the cap is shown with a somewhat different form of ridges and grooves 26 having beveled sides to engage tightly the top of the neck of the bottle.

As in the other form of the invention, the nozzle or spray portion of the device is made in the form of an upward external projection 27 provided with an internal passage 28. The passage 28, as in the other form of the device, is preferably made square or of some other polygonal shape in cross section and its upper end is terminated by an inclined wall 29. In this instance, however, the inclined wall 29 preferably extends from one corner of the passage 28 diagonally upward at a suitable angle such as 45° toward the opposite corner of the passage 28. Externally the projection 27 is cut away along a plane at substantially right angles to the plane of the wall 29, sufficient material being cut away from the outside of the projection 27 to leave the small opening 31. In this case it will be apparent that the opening 31 will be triangular in shape because of the relative disposition of the wall 29 and the cut away portion 30 with relation to the square passage 28. A tubular member 32 having a central opening 33 is fitted tightly or pressed into the passage 28 of the nozzle before the nozzle and cap are applied to the bottle. The length of the tube is adjusted so that it will extend almost but not quite to the bottom of the bottle on which the cap is to be applied.

While the wall 19 in one case and the wall 29 in the other form of the device have been mentioned as inclined at an angle of 45° to the horizontal, or to the vertical as the case may be, it will be noted that this angle may be varied considerably and governs the direction in which a spray is projected from the nozzle when a bottle containing liquid and fitted with one of these nozzle caps is squeezed. Thus, the spray does not shoot straight up from the top of the bottle but is projected at a suitable angle which makes it particularly convenient for dispensing various liquids such as perfumes, deodorants and the like, or for dispensing various powders.

The terms and expressions which we have employed are used as terms of description and not of limitation, and we have no intention, in the use of such terms and expressions, of excluding any equivalents of the features shown and described or portions thereof, but recognize that various modifications are possible within the scope of the invention claimed.

We claim:

65 A spray cap having a substantially cylindrical side wall and a top wall integral therewith, screw threads formed on the inside of the cylindrical side wall, a vertical projection formed on top of the top wall, integrally therewith, a biased face 70 on said vertical projection which is inclined at an angle of approximately 45 degrees with respect to the central axis of said vertical projection, a vertically extending passageway formed in said vertical projection, a biased wall formed 75 in said vertical projection at the top of said ver-

tical passageway, said wall being inclined at an angle of approximately 45 degrees with respect to the central axis of said vertical projection and being also disposed in perpendicular relation to the biased face on said vertical projection, an opening formed in said biased face which communicates with the vertical passageway immediately adjacent said biased wall, and a tube whose upper end projects upwardly into said vertical passageway, said passageway being rectangular in cross-section and said tube being circular in cross-section to provide corner spaces between said tube and the corners of said vertical passageway, said corner spaces and said tube itself being in communication with the atmosphere through the opening in the biased face, the biased wall at the top of the vertical passageway being inclined at an angle of approximately 45° with respect to two opposite walls of the rectangular vertical passageway, said biased wall rising from the top of one of said opposite walls and extending upwardly toward the other of said opposite side walls, the opening in the biased face being formed between the top of said biased wall and the top of said other opposite wall of the ver- 25

tical passageway, said opening being rectangular in shape, one of its side edges coinciding with said biased wall and the other side edge coinciding with said other opposite side wall of the vertical passageway.
